UNITED STATES PATENT OFFICE.

CHAUNCEY C. MEDBERY, OF NEW YORK, N. Y.

ORE-TREATING FURNACE.

No. 922,609.

Specification of Letters Patent.

Patented May 25, 1909.

Application filed January 15, 1909. Serial No. 472,399.

To all whom it may concern:

Be it known that I, CHAUNCEY C. MEDBERY, a citizen of the United States, and a resident of New York, county and State of New York, have invented Improvements in Ore-Treating Furnaces, of which the following is a specification.

The rotary continuous ore treating furnace forming the subject of this invention comprises cylinders lined with refractory material suitably mounted at different heights and reversibly inclined, an end support connecting the lower end of an upper cylinder to the upper end of a lower cylinder, means for rotating the cylinders, means for feeding ore to the upper end of the uppermost cylinder, and fuel supply device located at the lower end of the lowest cylinder. By this arrangement of parts the construction and operation of ore treating furnaces of this character, requiring chambers sufficiently long to insure the thorough melting of the ore passing through them, are greatly facilitated. Considerable space is saved, as each cylinder, according to the number, need be according to the number used only proportionately as long as a single cylindrical furnace having the same ore treating capacity to provide for the necessary time of transit of the ore through the furnace; the length of a single cylinder being also controlled by practical limitations. It further provides further advantageous features, for instance an ore that requires roasting may as continuing processes under one heating be roasted and heated in an upper cylinder or cylinders and then smelted in a lower cylinder or cylinders.

Another feature of this invention lies in applying a fore-hearth to receive the molten minerals (metal and slag) as they flow in a continuous stream from the discharge end of the furnace; said fore-hearth having sufficient capacity for the accumulation of considerable metal which is drawn off from its lower part from time to time, while the slag flows in a continuous stream from its upper part, and this fore-hearth is designed to be heated by the waste heat of the products of combustion from the furnace, provisions therefor being preferably made by flues formed in the walls of the fore-hearth.

The invention further consists in the combination with rotary cylinder furnaces of generators of suitable construction adapted to be alternately heated by the gaseous

products of combustion leaving the feeding end of the furnace, and alternately afford passages, when heated, to raise the temperature of the fuel (gas and air) as it passes to the furnace; and in a system of gates and valves in the various pipes and passages so connected as to be simultaneously operated, which may be automatically done, at suitable regular intervals.

Other novel features of construction pertaining to rotary continuous ore treating furnaces will, with the main features above set forth, be now fully described by reference had to the accompanying drawings, in which:

Figure 1 is a side elevation of a furnace showing an embodiment of my invention, with some parts broken away to show the internal construction; Fig. 2 is a front elevation, partly in section; Fig. 3 is an elevation, partly in section, of the return fuel connector at the rear ends of the cylinders; Fig. 4 is a longitudinal section of the same; Fig. 5 is a horizontal section showing the discharge end of the lower cylinder and the fuel supply nozzles, taken on the line 5, 5, Fig. 2; Fig. 6 is a plan view of the fore-hearth, in section on line 6, 6, Fig. 7; Fig. 7 is a longitudinal section of the same showing a side wall broken away; Fig. 8 is a side elevation of the forward part of a modification of the invention, whereby the combined process of roasting and smelting ores may be perfectly carried out, and Fig. 9 is a front view of the same, partly in section.

For most purposes and general use it is thought that in place of one long cylinder of a rotary continuous furnace two sections or two short cylinders located one above the other, as shown in the drawings, will be sufficient.

The two cylinders *a* and *b* are supported and held in place, reversely inclined, by suitable roller bearings *c* and *d* respectively carried by supporting frames and bearing rings *e*, *e* on the cylinders. The means shown for rotating the cylinders consists of gear rings *f* and *g* attached to the cylinders *a* and *b* and actuating gears *h* and *i* respectively, independently driven from any suitable source of power, so that the cylinders may be rotated at different speeds as may be expedient in governing the speeds of travel of the minerals through the cylinders; the driving gears being shown provided with cone pulleys *j*, *k* for this purpose.

The front ends of the cylinders, that is the high end of the cylinder *a* and the low end of the cylinder *b* are fitted to rotate in a front frame *l*, and the rear ends of the cylinders, that is the low end of the cylinder *a* and the high end of the cylinder *b* are fitted to rotate in the frame *m* of the return flue connector *n* of the cylinders.

Side passages in the front frame *l* afford 10 communication between the chambers into which the front ends of the cylinders open and are filled with checker work, constituting the regenerators, and each passage is by a vertical wall *o* divided into two parts *p* 15 and *q*, thus forming a pair of regenerators at each side of the furnace, the parts *p* providing passages for the air and the parts *q* passages for the gas of the gaseous fuel. The air and gas passages although shown of 20 equal size in the drawings may, as will be well understood, be made of different capacities.

An air supply pipe *r* by branches *s*, *s* connects with the upper ends of the passages *p* of the regenerators, and a gas pipe *t*, by 25 branches *u* connects with the upper ends of the passages *q*. The air and gas pass from the regenerators into the mixing chamber *v* and issue therefrom by the nozzle *w* into the discharge end of the lower cylinder *b*. 30 The regenerator passages continue downwardly into dust collecting pockets *x*, *x*, closed by doors *y*, and just above these pockets are side openings *z* through which the heated gaseous products of combustion escape after passing through the regenerators. 35

The fore-hearth 1 is rectangular in shape, is adapted to fit between the lower part of the side legs of the front frame, and is provided with wheels 2 resting on rails, whereby 40 it may be moved from the furnace for repairs &c. Its open upper side is covered by the chamber into which the lower end of the cylinder *b* extends and by an arch 3 extending from the front frame *l* as a continuation 45 of said chamber. At the front of the arch 3 is a burner nozzle 4 adapted to supply a gaseous fuel above the mass in the fore-hearth so as to assist in maintaining the slag in a molten condition, which escapes in a 50 continuous stream from the spout 5 when the fore-hearth is full; the metals being drawn off, from time to time, at the spout 6 located at the lower part of the fore-hearth, and plugged in the usual manner.

55 The fore-hearth consists of a metal rectangular casing lined at the sides and bottom with a refractory material provided with horizontal passages 7, 7, the upper and second passages being connected by vertical 60 openings 8, 8, the second and third by openings 9, 9, the third and fourth by openings 10, 10, and so on to the hollow bottom 11, which by a central opening and connecting pipe 12 communicates with a discharge flue 65 13 when the fore-hearth is set in operative

position. The passages 7, 7 are divided by vertical partitions 14, 14. The upper passages 7, 7 have two openings 15, 15 at each side of the fore-hearth which align with the openings *z*, *z* in the chamber at the lower ends of the regenerators, so that heated products of combustion from the cylinder *a*, alternately flowing through the regenerators, will pass alternately through the openings 15, 15 at the two sides of the fore-hearth into 75 the upper passages 7, 7, where they divide and flow right and left through all the horizontal passages and finally escape through the opening and connecting pipe 12, thereby keeping the fore-hearth heated, to maintain 80 the minerals therein in a molten condition, sufficiently intense that with the large capacity of the fore-hearth will insure a complete precipitation of all of the values or metals from the molten mass. 85

Ore is continuously fed to the high end of the cylinder *a* from the hopper 16 by any suitable means, as a screw conveyer 17. In the air and gas pipes and at the communications between the various flues and passages are located gates or valves to direct the flow of the air and gas and the heated products of combustion from the cylinder *a* alternately to the two pairs of regenerators. The air pipe has a valve 18 adapted to cause 95 the air to flow through either of the branches *s* and the gas pipe has a valve 19 for similarly controlling the flow of the gas. In the branches *s* and *u* of the air and gas pipes are check valves 20 and 21 to cut off the heat of 100 the regenerators from the supply pipes and their controlling valves. At the sides of the chamber into which the upper end of the cylinder *a* opens are shown sliding gates or valves for closing communication between 105 said chamber and the upper end of the regenerators, and below the regenerators are located pivotal valves 23, 23 whose functions are to close the openings to the mixing chamber *v* through which the heated air and gas 110 flow and to close communication between the regenerators and the fore-hearth. In the operation of the furnace these gates or valves are reversely set at the two sides of the cylinders, as shown at Fig. 2, that is the air and gas valves 18 and 19 are set to allow the gases to enter the regenerators at the left hand, the check valve 20 at this side being also opened, the gate 22 is closed and the pivotal valve 23 is set horizontally to cut 115 off communication to the fore-hearth and open the mixing chamber of the burner nozzle to the pair of regenerators. At the right hand the pair of regenerators is open to the upper cylinder *a*, the gate 22 being raised, the air and gas valves 18 and 19 and the check valves 20, 20 closed, and the pivotal valve 23 set vertically so as to cut off the burner nozzle *w* and open communication 120 between the cylinder *a* and the fore-hearth 130

through the regenerators at the side of the furnace. After the furnace has been run with the valves &c. set as just described for a fixed interval of time, to properly heat the 5 left hand pair of regenerators, the positions of all of the valves &c. are then reversed to heat up the left hand regenerators and cause the air and gas to flow through the right hand regenerators, and as it is advantageous 10 to move all the valves &c. simultaneously suitable connecting and operating devices are shown, consisting of a sprocket wheel 24, which may be motor driven but is shown with an operating handle, a chain 25 connecting this wheel to a sprocket wheel 26 on a shaft located at the upper part of the furnace; racks and pinions 27, 27 for operating the gates 22, 22, chains 28, 28 connecting the shafts of these pinions to the shaft of the 15 sprocket 26, links 29, 29 pivoted to the upper ends of the gates 22, 22, and the arms 30, 30 on the shaft of the pivotal valves 23, 23, a link 31 joining the upper end of one of the gates 22 to the end of an arm 32 connected to 20 the shaft of a pinion 33, another arm 34 on this shaft connected to the arm of one of the valves 20 by a link 35, a link 36 connecting the arm of this valve 20 to the arm of the other arm 20, and a segmental gear 37 on the 25 shaft of the valves 18 and 19, and into which meshes the pinion 33.

The connector *m* at the rear ends of the cylinders *a* and *b* with the return flue *n* is supported by a suitable frame 38, all of its 30 inner exposed surfaces of the upper part are covered by a refractory material and its lower part, which constitutes a chute 39 to direct the ore as it falls from the upper cylinder *a* into the lower cylinder *b*, is of metal 35 and adequately water jacketed, the inlet and outlet pipes controlling the water supply thereto being indicated at 40 and 41. Above the chute 39 is an opening 42, covered by a door, for the insertion of a barring down tool 40 to clear the chute should it become clogged; and above this opening 42 is a pipe 43 to direct gases to the lower end of the upper cylinder *a*, which gases will be of the nature of a fuel when it is desired to apply more heat to 45 the upper cylinder than will pass thereto from the lower cylinder, or of a re-acting nature when the upper cylinder is used in a roasting proposition. A peep-hole 44 is provided in the return flue connector for the visual examination of the processes in the cylinder *a*. A peep-hole 45 is also provided in the end of the arm 3 for the examination of the interior of the lower cylinder *b*.

In the treatment of some ores that require 50 to be roasted before being smelted the roasting process may be carried out in the upper cylinder *a*, and to meet the cases where the time of transit of the ore through a roasting cylinder to thoroughly roast it might re-

ceed that of the time of its transit through the smelting cylinder then it is proposed to increase the length of the upper cylinder, which may be done in the manner shown at Figs. 8 and 9, which illustrates the necessary modifications in the construction of the front 55 end of the furnace, the rear end and all the essential features being as heretofore shown and described. The upper end of the elongated cylinder 46 rotates in upper part 47 of the front frame *l*, which is supported by 60 standard frames 48, 48; the regenerators in this case have their upper parts 49, 49 arranged horizontally and by curved bends communicate with burner at the lower end of the lower cylinder and the fore-hearth. 65 All of the valves &c. and parts similar to those described and shown in the other drawings are correspondingly designated, and their operations similar, so a further reference to them is unnecessary.

I claim as my invention:—

1. The combination with a rotary cylinder furnace, means for feeding ore thereto at one end and means for supplying a gaseous fuel at the other end, of regenerators through which 70 the products of combustion from the cylinder furnace and the gaseous fuel, air and gas, alternately pass, and a fore-hearth also heated by the products of combustion and into which flow the melted minerals from the 75 furnace.

2. The combination with a rotary cylinder furnace, means for feeding ore thereto at one end and means for supplying a gaseous fuel at the other end, of two pairs of regenerators 80 located at the feeding end of the furnace alternately heated by the products of combustion from the furnace and alternately imparting their heat to the air and gas of the fuel supplied to the furnace, and a fore-hearth 85 for receiving the melted minerals from the furnace and adapted to be heated by the products of combustion.

3. The combination with a rotary cylinder furnace, means for feeding ore thereto at one 90 end and means for supplying a gaseous fuel at the other end, of two pairs of regenerators located at the feeding end of the furnace alternately heated by the products of combustion from the furnace and alternately imparting their heat to the air and gas of the fuel supplied to the furnace, and a fore-hearth 95 for receiving the melted minerals from the furnace and adapted to be heated by the products of combustion, gates or valves 100 located between the side arms ends of the regenerators and the furnace, and a pipe 105 connecting the upper end of the pipe 105 to the upper end of the cylinder 110.

4. The combination with a rotary cylinder furnace, means for feeding ore thereto at one end and means for supplying a gaseous fuel at the other end, of two pairs of regenerators located at the feeding end of the furnace alternately heated by the products of combustion, gates or valves 115 located between the side arms ends of the regenerators and the furnace, and a pipe 120 connecting the upper end of the pipe 120 to the upper end of the cylinder 125.

- to the regenerators, and means for simultaneously unionally actuating all of the gates or valves.
4. The combination with a rotary cylinder 5 furnace, means for feeding ore thereto at one end and means for supplying a gaseous fuel at the other end, a fore-hearth into which the molten minerals from the furnace run, and a flue or passage for directing the products of 10 combustion from the furnace to the fore-hearth.
5. A fore-hearth for receiving molten minerals from an ore treating furnace having passages formed in its walls through which 15 heated gases may be caused to pass, a spout at the upper part for the continuous discharge of the slag and a spout at the lower part for drawing off the metals.
6. A movable fore-hearth for receiving 20 molten minerals from a furnace having passages formed in its walls with inlet openings at the upper part and an outlet opening at the lower part, in combination with a flue adapted to connect with and direct heated 25 gases to the inlet openings and a discharge pipe adapted to connect with the outlet opening when the fore-hearth is set in operative position.
7. A movable fore-hearth for receiving 30 molten minerals from a furnace having a series of horizontal passages vertically connected at different parts formed in its walls and bottom with inlet openings at the upper part and an outlet opening at the lower part, 35 in combination with a flue adapted to connect with and direct heated gases to the inlet openings and a discharge pipe adapted to connect with the outlet opening when the fore-hearth is set in operative position.
- 40 8. An ore treating furnace comprising two cylinders reversely inclined and arranged one higher than the other, means for feeding ore to the high end of the upper one, means for supplying a gaseous fuel at the low end of the 45 lower one, and a return flue connector joining the low end of the upper cylinder and the high end of the lower cylinder and having a guide chute over which the ore passes from the upper to the lower cylinder, and a barring 50 down opening above the chute.
9. An ore treating furnace comprising two cylinders reversely inclined and arranged one higher than the other, means for feeding ore to the high end of the upper one, means for 55 supplying a gaseous fuel at the low end of the lower one, and a return flue connector provided with a water jacket at the lower part and joining the low end of the upper cylinder and the high end of the lower cylinder through 60 which the ore passes from the upper to the lower cylinder.
10. An ore treating furnace comprising two cylinders reversely inclined and arranged one higher than the other, means for feeding 65 ore to the high end of the upper one, means for supplying a gaseous fuel at the low end of the lower one, and a return flue connector having a water jacket at the lower part and joining the low end of the upper cylinder and the high end of the lower cylinder through which the ore passes from the upper to the lower cylinder.
11. A movable fore-hearth for receiving 70 molten minerals from a furnace having a series of horizontal passages vertically connected at different parts formed in its walls and bottom with inlet openings at the upper part and an outlet opening at the lower part, 75 in combination with a flue adapted to connect with and direct heated gases to the inlet openings and a discharge pipe adapted to connect with the outlet opening when the fore-hearth is set in operative position, in combination with a stationary arch hood over the fore-hearth and a burner nozzle passing through the end wall of the hood for applying heat to the surface of the contents of the fore-hearth.
12. The combination with two rotary furnaces cylinders reversely inclined and arranged one higher than the other, means for feeding ore to the high end of the upper cylinder, means for supplying a gaseous fuel to the low end of the lower cylinder, of regenerators through which the products of combustion from the cylinder furnace and the gaseous fuel, air and gas, alternately pass, a return flue connector having suitable openings in which the ends of the cylinders rotate, a water jacket at the lower part of the return flue connector, and a nozzle passing through the return flue connector adapted to supply a stream of gas to the lower end of the upper cylinder.
13. The combination with two rotary furnaces cylinders reversely inclined and arranged one higher than the other, means for feeding ore to the high end of the upper cylinder, means for supplying a gaseous fuel to the low end of the lower cylinder, of regenerators through which the products of combustion from the cylinder furnace and the gaseous fuel, air and gas, alternately pass, a return flue connector having suitable openings in which the ends of the cylinders rotate, a water jacket at the lower part of the return flue connector, and a nozzle passing through the return flue connector adapted to supply a stream of gas to the lower end of the upper cylinder, a peep hole located near the nozzle, and a barring down hole located above the water jacket.
14. An ore treating furnace comprising two cylinders reversely inclined and arranged one higher than the other, means for feeding ore to the high end of the upper one, means for supplying a gaseous fuel at the low end of the lower one, a return flue connector having a water jacket at the lower part and joining the low end of the upper cylinder and the high end of the lower cylinder through which the ore passes from the upper to the lower cylinder.

5 nector joining the low end of the upper cylinder and the high end of the lower cylinder through which the ore passes from the upper to the lower cylinder, a front frame in which the other ends of the cylinders are fitted to rotate, a fore-hearth located beneath the low end of the lower cylinder and heated by the gaseous products of combustion discharged from the high end of the upper cylinder, means for supporting and means for independently rotating the cylinders.

10 15 20 25 30 35 40 45 50 55 60 65 70 75 80 85 90 95 100 105 110 115 120 125 130

15. An ore treating furnace comprising two cylinders reversely inclined and arranged one higher than the other, means for feeding ore to the high end of the upper one, means for supplying a gaseous fuel at the low end of the lower one, and a return flue connector joining the low end of the upper cylinder and the high end of the lower cylinder through which the ore passes from the upper to the lower cylinder, a front frame in which the other ends of the cylinders are fitted to rotate, means for supporting and means for independently rotating the cylinders, regenerators in the front frame through which the gaseous products of combustion from the upper cylinder are by suitable valves caused to alternately pass, and through which, as they become alternately heated, the gaseous fuel is caused to flow before it enters the lower end of the lower cylinder.

16. An ore treating furnace comprising two cylinders reversely inclined and arranged one higher than the other, means for feeding ore to the high end of the upper one, means for supplying a gaseous fuel at the low end of the lower one, and a return flue connector joining the low end of the upper cylinder and the high end of the lower cylinder through which the ore passes from the upper to the lower cylinder, a front frame in which the other ends of the cylinders are fitted to rotate, means for supporting and means for independently rotating the cylinders, two pairs of regenerators in the front frame affording communication between the two cylinders, gas and air supply pipes, a mixing chamber at the lower end of the lower cylinder, valves or gates in said pipes and at the ends of the regenerators by the manipulation of which the hot gaseous products of combustion from the upper cylinder and the air and gas of the fuel are caused to alternately pass.

17. An ore treating furnace comprising two cylinders reversely inclined and arranged one higher than the other, means for feeding ore to the high end of the upper one, means for supplying a gaseous fuel at the low end of the lower one, and a return flue connector joining the low end of the upper cylinder and the high end of the lower cylinder through which the ore passes from the upper to the lower cylinder, a front frame in which the other ends of the cylinders are fitted to rotate, means for supporting and means for in-

dependently rotating the cylinders, two pairs of regenerators in the front frame affording communication between the two cylinders, gas and air supply pipes, a mixing chamber at the lower end of the lower cylinder, valves or gates in said pipes and at the ends of the regenerators by the manipulation of which the hot gaseous products of combustion from the upper cylinder and the air and gas of the fuel are caused to alternately pass, and dirt discharge openings at the lower ends of the regenerators.

18. An ore treating furnace comprising two cylinders reversely inclined and arranged one higher than the other, means for feeding ore to the high end of the upper one, means for supplying a gaseous fuel at the low end of the lower one, and a return flue connector joining the low end of the upper cylinder and the high end of the lower cylinder through which the ore passes from the upper to the lower cylinder, a front frame in which the other ends of the cylinders are fitted to rotate, means for supporting and means for independently rotating the cylinders, regenerators in the front frame through which the gaseous products of combustion from the upper cylinder are by suitable valves caused to alternately pass, and through which, as they become alternately heated, the gaseous fuel is caused to flow before it enters the lower end of the lower cylinder, and a fore-hearth for receiving molten minerals, provided with heating passages in communication with the regenerators to receive the heated gases after they flow through the regenerators.

19. An ore treating furnace comprising two cylinders reversely inclined and arranged one higher than the other, means for feeding ore to the high end of the upper one, means for supplying a gaseous fuel at the low end of the lower one, and a return flue connector joining the low end of the upper cylinder and the high end of the lower cylinder through which the ore passes from the upper to the lower cylinder, a front frame in which the other ends of the cylinders are fitted to rotate, means for supporting and means for independently rotating the cylinders, regenerators in the front frame through which the gaseous products of combustion from the upper cylinder are by suitable valves caused to alternately pass, and through which, as they become alternately heated, the gaseous fuel is caused to flow before it enters the lower end of the lower cylinder, a fore-hearth into which the molten minerals flow from the lower cylinder and provided with passages in its walls in communication with and to receive the heated gases from the regenerators, and a nozzle above the fore-hearth for supplying fuel to maintain the upper part minerals in the fore-hearth in a molten condition.

20. The combination with a rotary cylin-

der furnace, means for feeding ore thereto at one end and means for supplying a gaseous fuel at the other end, of regenerators through which the products of combustion from the cylinder furnace and the gaseous fuel, air and gas, alternately pass, and a fore-hearth also heated by the products of combustion and into which flow the melted minerals from the furnace, and a burner nozzle for supplying fuel above the fore-hearth to maintain the surface of the molten mineral therein in a molten condition.

21. The combination with a rotary cylinder furnace, means for feeding ore thereto at one end and means for supplying a gaseous fuel at the other end, of two pairs of regenerators located at the feeding end of the furnace alternately heated by the products of com-

bustion from the furnace and alternately imparting their heat to the air and gas of the fuel supplied to the furnace, and a fore-hearth for receiving the melted minerals from the furnace and adapted to be heated by the products of combustion, a discharge spout at the upper part of the fore-hearth for the continuous flow of the slag therefrom, and a spout at the lower part for drawing off the metals.

In testimony whereof, I have hereunto subscribed my name, this 13th day of January, 1909.

CHAUNCEY C. MEDBERY.
